FRONT POLE ADJUSTMENT FOR LATERAL
ARM AWNINGS

Frederick A. Anton, Topeka, Kans.

Original application January 31, 1934, Serial No. 709,112, now Patent No. 2,038,259, dated April 21, 1936. Divided and this application February 17, 1936, Serial No. 64,353

12 Claims. (Cl. 156—44)

This invention relates to lateral arm awnings and forms a division of my application for patent filed January 31, 1934, Serial No. 709,112, issued as Patent No. 2,038,259, April 21, 1936. Modern store front constructions require the folding of lateral arm awnings in compact form. To insure this compactness of folding, the awning pole must cooperate with a stop provided on the outer end of the outer arm to insure that as the arms are folded back into position, the outer pivot shall not pass rearwardly of the intermediate pivot, as if such action occurs, the arms will be found to have become locked against opening movement.

Furthermore, it has been found, in actual practice, that because of slight variations in the mounting of the several brackets used to secure an awning to a building front, variations in diameter of castings, awning fittings and the like, it is practically always necessary, with present awning arms, to bend or distort the parts to insure proper folding operation. Where the arms are of finished stock or even are painted, it is impossible to accomplish this adjustment without marring the finish.

Therefore, with the general object in view of providing for an adjustable relation between the outer end of the outer arm and the awning pole or front board, the invention consists in certain novel and useful features of construction and organization of parts as hereinafter described and claimed; and in order that it may be fully understood, reference is to be had to the accompanying drawing, in which:—

Figure 1 is a top plan view of a lateral arm awning equipped with devices embodying the invention.

Figure 2 is an enlarged horizontal section taken through one of the devices or brackets, shown in Figure 1 as connecting the outer end of the outer arm to the awning pole or front board.

Figure 3 is an elevational view of the inner side of said bracket.

Figure 4 is an end view of the same.

In the said drawing, where like reference characters identify corresponding parts in all of the figures, the awning pole is shown as of tubular form, although it is to be understood that it may be a wooden pole or may be in the form of a front board, the parts being modified accordingly. For convenience of illustration, 1 is a wall bracket secured to the building front. Pivot to the bracket 1 around a bolt 19, is the inner end of the inner arm 20. The outer arm 32 at its inner end is provided with a fitting 55 which is pivoted

to a fitting 59 carried by the outer end of the inner arm 20. The outer end of the outer arm carries a suitable fitting 31 provided with a stop 36 for a purpose which will hereinafter appear, and the connection between said parts may be hidden or protected by a sleeve 50, if the parts happen to be of tubular shape as illustrated. These parts are not otherwise detailed as they may be of any desired construction.

As stated in the objects of the invention, in the modern type of lateral arm awning, compactness and neatness of folding is of prime importance and it has therefore been more and more necessary to insure that the lateral arms shall be pushed back into full folded position and held against danger of becoming locked in such position as above mentioned. It has, therefore, been necessary to provide the front end of the outer arm with an offset or stop portion, such as shown at 36, which comes into contact with the front pole at the proper time and insures that further swinging movement of the pole with relation to the awning arm, shall not occur. Stopping relative movement of the outer arm with relation to the front pole or board, insures that further swinging or closing movement must take place around the intermediate and inner arm pivots. If this stop contact does not occur at the proper time, it frequently happens that the awning arm or the front pole is bent or distorted, or the parts may move to awning-locked position.

To provide a device which is of universal use with any type of awning pole or front board, the construction shown in the drawing or its equivalent may be employed. As shown, the device comprises a tubular clamp sleeve 78 to be fitted on the front pole 79 in accordance with whether it is to receive a right or left hand arm as shown in Figure 1. One wall of the clamp sleeve 78 may be split longitudinally from its opposite ends as at 80, the opposite portions of the sleeve being bent outwardly to form a pair of spaced ears 81 and a pair of larger spaced ears 82. The intermediate portion of the split side wall of the sleeve 78 is formed integrally with an unsplit cage or housing 83. Mounted in the cage for movement transversely of the axis of the sleeve, is a rack member 84 which is held in position against rotation by a rib 84a, and is actuated back and forth by a bolt 85 in threaded relation therewith. The bolt 85 is held against longitudinal movement through engagement of its head 86 and a cotter pin 87 on opposite sides of the housing wall (see Figure 2).

The sleeve is transversely split as at 88 so that the clamp bolt 89 extending through the ears 81 may apply clamping pressure to hold the sleeve in position on the front pole 79. The opposite inner faces of the ears 82 are recessed to receive a pair of toothed disks 90, formed with a pair of registering openings receiving the bolt or pivot pin 91 which passes through an opening in the ear 41 carried by the fitting 31 secured to 10 the outer end of the outer arm.

The ends of the bolt 91 project through arcuate slots 92 in the ears 82 so that by movement of the toothed disks 90 imparted by the rack member, the position of the pivot 91 may be adjusted toward and from the longitudinal axis of 15 the front pole or board. When it is desired to adjust the pivot, it is loosened, then the disks are rotated to shift the bolt in the desired direction, and the bolt is then retightened to apply 20 clamping pressure on the front pole to assist the bolt 89 in holding the device against slipping and also to bind all of the parts against vibration. By reference to Figure 1, it will be 25 evident that the closer the longitudinal axis of the front pole to the axis of the pivot bolt, the earlier the contact of the stop 36 with the front pole.

After installation of an awning, the operator 30 adjusts the pivot bolts for the proper folding operation of each of the awning arms, it being apparent that an adjustment of a fraction of an inch at this point is magnified by the length of the outer arm to effect a fairly wide swing or adjustment in the position of the center pivot connecting 35 the two arms together. The exact time of contact of the stop with the front pole as regards the position of the center pivot connecting the arms, can only be determined by experiment with an installation.

40 From the above description, it will be apparent that I have produced a construction embodying all of the features of advantage pointed out as desirable, and it is to be understood that while I have described and illustrated the preferred embodiment, I reserve the right to all changes within the spirit of the invention and without the ambit of the prior art.

I claim:

1. In a lateral arm awning construction, a 50 front pole, an awning arm, a pivotal connection between said members, and means for adjusting the axis of said connection toward and from the longitudinal axis of the front pole.

2. In lateral arm awning construction, a front 55 connection comprising a member for attachment to a front pole, a pivot pin carried by said member in angular relation to the longitudinal axis of the front pole, and means for disposing the axis of said pivot pin toward and from the longitudinal axis of the front pole.

3. The combination in a lateral arm awning, 60 of a pivotal connection between the front pole and the outer end of the outer arm, and means

for effecting relative approaching and receding movements between said pivotal connection and the front pole.

4. A fitting for lateral arm awning arms comprising a bracket adapted to be secured to a front pole, an element movable on the bracket, and a pivot pin carried by said element and adapted to receive the outer end of an awning arm. 5

5. A fitting for lateral arm awning arms comprising a bracket adapted to be secured to a front pole, a pivot pin associated with said bracket and adapted to receive the end of one of the awning arms, and mechanism for effecting adjustment of the pin toward and from the axis of the front pole. 10

6. A fitting for lateral arm awning arms comprising a bracket adapted to be secured to a front pole, a rotatable disk mounted on said bracket, a pivot pin carried by said disk and adapted to receive the outer end of a lateral awning arm, and means for rotating said disk. 15

7. A fitting for lateral arm awning arms comprising a bracket adapted to be secured to a front pole, a rotatable disk mounted in the bracket, a pivot pin carried by said disk and adapted to receive the outer end of a lateral arm, and a bolt operatively associated with said disk to effect rotation of the same. 20

8. A fitting for lateral arm awning arms comprising a bracket adapted to be secured to a front pole, a circular socket in said bracket, a toothed disk mounted in the socket, a pivot pin eccentrically mounted in the disk and adapted to be secured to the outer end of an awning arm, and means enmeshed with the teeth of the disk 25 to impart rotation to the same.

9. A fitting for lateral arm awning arms comprising a bracket adapted to be secured to the front pole, a threaded bolt carried by the bracket, a movable element carried by the bracket and 40 actuated by the bolt, and a pivot pin secured in the movable element and adapted to receive the outer end of an awning arm.

10. The combination in a lateral arm awning of a lateral arm and a front pole, a pivotal connection between the front pole and lateral arm, and means for progressively shifting the axis of 45 said pivotal connection toward and from the front pole.

11. The combination in a lateral arm awning 50 of a front pole, a split sleeve in clamping engagement therewith, an element movably carried by the sleeve, a pivot pin carried by said element, and a lateral arm secured to said pin.

12. The combination in a lateral arm awning 55 of a front pole, a split sleeve in clamped engagement therewith, a rotatable member carried by the sleeve, a pivot pin carried eccentrically by said rotatable member, means to rotate said member, and an awning arm secured to said 60 pivot pin.

FREDERICK A. ANTON.
